IRVING E. ASKE, OF MINNEAPOLIS, MINNESOTA

CYLINDER HEAD FOR INTERNAL-EXPLOSION ENGINES

Application filed March 12, 1928, Serial No. 261,083. Renewed July 2, 1930.

My invention relates to cylinder heads for internal explosion engines, and has for its object the provision of an improved cylinder head adapted to avoid material accumulations 5 thereon of carbon and rust.

Engineers and mechanics are well acquainted with the troubles, including knocking, arising from the accumulation of carbon on the combustion chamber side of the cylinder head, but no attention seems to have been given to the rust, dirt and scale that accumulates on the face of said head which is exposed to the cooling liquid, or to materially reducing the thickness of the combustion 15 chamber cover.

It is common to make such cylinder heads of cast iron, which tends to rust, and to which scale and sediment readily adhere; which heads are also required to be made thick and 20 heavy to withstand the pressure of the fuel explosion.

In many localities the quality or character 25 of the cooling water or liquid is such that it tends to deposit large quantities of scale or sediment upon the cylinder head whereby the cylinder head is prevented from rapidly radiating its excessive heat into the cooling liquid.

I have observed that knocking occurs in 30 high compression engines even when highly volatile gasoline hydrocarbon composition or mixture is used as fuel, and I am confident that in such case the knocking is in large measure due to rust, scale, or sediment on the 35 face of the cylinder head which is exposed to the cooling liquid and to the thickness of the combustion chamber cover whereby radiation is retarded. Since the compression ratios 40 generally approved by the art appear to be rapidly advancing or growing higher, it is urgent that a cylinder head structure be devised which will withstand the greater strains of fuel explosions and which will very rapidly 45 transmit the excessive heat to the cooling liquid.

One object of my invention is the provision 50 of a cheap, durable liquid cooled cylinder head containing a cooling liquid circulation chamber and embodying a thin heat transmitting, rust and scale resisting partition plate or dia-

phragm common to said circulation chamber and to the combustion chamber of said cylinder. With these and other objects in view, my invention consists of the structures, combinations and arrangements of parts herein- 55 after described and claimed.

In the drawings, Fig. 1, is a bottom plan view of a cylinder head embodying one form of my said invention. Fig. 2, is a vertical longitudinal section through said cylinder 60 head on the line A—B of Fig. 1. Fig. 3 is a bottom plan view of one form of the herein- 65 after described partition plate. Fig. 4, is an edge view of said partition plate. Fig. 5, is a vertical transverse section of said cylinder 65 head on the line C—D of Fig. 1. Fig. 6 is a top plan view of a modified form of said plate, and Fig. 7, is a side elevation of said modified form.

In the drawings, 1 is a thin steel partition 70 plate of any suitable vertical and horizontal contours, positioned between the cover 2 of a liquid circulation chamber 2a, and the combustion chamber of an internal explosion engine (not shown, but well known to the art); 75 said partition plate being common to said circulation and explosion chambers and adapted to form a partition there-between. The surfaces of said partition plate are preferably smoothed or highly polished and are 80 of any suitable heat enduring and conducting and rust resisting material, which may for example, be provided by plating the partition plate with chromium, or by constructing it entirely of chromium steel. 85

Said plate is apertured as at 1a for the 90 passage of a socket 2b formed on said cover for the reception of a spark plug (not shown, but well known to the art), and said plate is welded at its periphery in any suitable manner to said liquid chamber cover, preferably to an inwardly directed flange or shoulder 2c formed on said cover and adapted to overlap the cooling chamber face of said plate for a short distance. Said plate is preferably 95 also welded at the edge of said aperture to an annular shoulder 2d formed on said socket and adapted to overlap the cooling chamber face of said plate for a short distance.

Said cover is provided at any suitable point 100

or points with ports, as at 2e, 2e, adapted to communicate with the liquid chamber within said cylinder head and with water circulation conduits (not shown) exterior to said head. 8 Bolt holes 2f are provided in said cover for the passage of bolts to secure said cylinder head in operative position upon the cylinder. 10 In operation, said plate by reason of its rust resistant surface material, and its polished surfaces and clear area offers no effective lodgment to carbon on its combustion chamber side, or to rust, scale or sediment on its liquid circulation side, said carbon being blown out by the exhaust and said scale or 15 sediment being washed away by the cooling liquid.

By welding said partition plate to said cover, better transmission of heat between the edge of said plate and said cover is secured. Said flange and shoulder of thick metal form substantial abutments for the thin steel plate, and by constructing said plate of steel, I am enabled to make it thin and of high 20 radiation capacity.

25 I am aware that a two-piece cylinder head containing a water circulation chamber and comprising a circulation chamber cover and a partition member detachable from said cover, said partition member having a spark plug socket formed therein, is per se, old; but my claims are not intended to cover such 30 structure.

What I claim is—

1. A combustion chamber head containing 35 a liquid circulation chamber and comprising a cover for said circulation chamber, said cover having a depending spark plug socket formed thereon, said cover having an inwardly directed flange formed thereon and 40 said socket having a peripheral shoulder formed thereon, and a partition plate common to said circulation and combustion chambers, said partition plate being apertured for the passage of said socket, said partition plate 45 overlapping said flange and shoulder and being welded thereto.

2. A combustion chamber head containing 50 a liquid circulation chamber and comprising a cover for said circulation chamber, said cover having a spark plug socket formed thereon, a partition plate common to said combustion and circulation chambers and embodying a rust resisting surface, said plate being apertured for the passage of one end 55 of said plug socket, said plate being welded at its periphery to said cover and at the rim of said aperture to said socket.

3. A combustion chamber head containing 60 a liquid circulation chamber and comprising a cover for said circulation chamber, said cover having a spark plug socket formed thereon, and a polished non-corrosive partition plate common to said combustion and circulation chambers, said plate being apertured for the passage of one end of said plug 65

socket, said plate being welded at its periphery to said cover and at the rim of said aperture to said plug socket.

4. A combustion chamber head containing a liquid circulation chamber and comprising 70 a cover for said circulation chamber, and a partition plate common to said combustion and circulation chambers, said plate being provided with a polished non-corrosive surface upon its circulation chamber side, said 75 plate being welded to said cover at its periphery.

In testimony whereof, I hereunto affix my signature.

IRVING E. ASKE.
